ELECTRICALLY-OPERATED BARBER POLE

Application filed December 24, 1928. Serial No. 328,224.

This invention relates to barber poles of the type that comprise a rotatable cylinder provided with conventional barber pole stripes.

The main object of our invention is to provide an electrically-operated barber pole of the general type mentioned, that is inexpensive to manufacture, easy to assemble and of such construction that there is little liability of the operating mechanism for the rotatable striped member failing to operate properly when the pole is in use.

To this end we have devised a barber pole that comprises a rotatable striped member, a driving means for said member, and an electric induction motor of the disk type for actuating said driving means.

Figure 1 of the drawings is a side elevational view of our improved barber pole.

Figure 2 is an enlarged fragmentary vertical sectional view of said pole.

Figure 3 is a horizontal sectional view, taken on the line 3—3 of Figure 2.

Figure 4 is a fragmentary vertical sectional view of our pole, illustrating another type of driving means that may be used; and

Figure 5 is a horizontal sectional view, taken on the line 5—5 of Figure 4.

Referring to Figures 1 to 3 of the drawings, which illustrate the preferred form of our invention, A designates a rotatable cylindrical member provided with conventional barber pole stripes, B designates a transparent casing for said member, formed preferably from a glass cylinder, and C designates top and bottom supporting brackets which are preferably provided with annular-shaped portions or collars that receive the upper and lower end portions of the glass cylinder B.

The operating mechanism for the striped member A is composed of an electric induction motor of the disk type, and a friction driving means for transmitting rotary motion from the disk of said motor to the member A, said motor and driving means being preferably carried by a supporting frame D that is detachably connected by screws 1 or in any other suitable way to the bottom supporting bracket C, as shown in

Figure 2. The coil α of said motor is ar-

ranged horizontally and the disk γ of said motor is arranged vertically. The driving means comprises a horizontally-disposed shaft 2 connected to the disk γ of the motor, and a disk-shaped friction-driving device 3 fastened to said shaft 2 and arranged to act upon the member A, preferably the bottom of said member. When the coil α of the motor is energized, the disk γ of the motor revolves, and thus causes rotary movement to be imparted to the member A, due to the frictional pressure which the driving device 3 exerts on the bottom of the member A, said member A being mounted in such a way that the weight of the same causes the bottom of said member to remain in frictional contact with the driving device 3. The member A is centered and maintained in operative relationship with the driving device 3 by a stationary centering pin 4 carried by the supporting frame D and arranged so that it will project upwardly into a hole in the bottom of the rotatable member A.

In order that the pole may operate properly for a long period without requiring attention, we have equipped it with a lubricating means, which, after being filled with oil or some other suitable lubricating medium, will keep the bearings of the drive shaft 2 in a properly lubricated condition. Said lubricating means comprises pockets or reservoirs 5 containing a lubricating medium, arranged in proximity to or combined with the bearings of the drive shaft 2 in such a way as to lubricate the portions of the drive shaft that turn in said bearings, and a conduit 6 accessible from the exterior of the pole for supplying oil or some other suitable lubricant to the pockets 5. In the form of our invention herein shown the pockets 5 are filled with oil soaked waste, and the oil supply conduit comprises a branched or yoke-shaped portion that leads to both of said pockets and a vertically-disposed portion 6^a whose upper end terminates in the top face of the bottom supporting bracket C, as shown more clearly in Figure 3, thereby enabling the supply of oil for the lubricating means to be easily replenished.

Due to the fact that the operating means

for the rotatable striped member A is combined with the frame D to form a unit that can be easily connected with or detached from the bottom supporting bracket C, the parts of the pole can be easily assembled and disassembled, it being preferable to provide the frame D with an insulating block 7 that carries binding posts 8 to which are connected wires 9 that lead to the coil α of the motor and supply wires 9^a that lead outwardly through a tubular portion 10 of the bottom supporting bracket C. When the parts of the pole are assembled, as shown in Figure 2, the centering pin 4 carried by the frame D, holds the rotatable member A in concentric relationship with the glass cylinder B that surrounds said member, and the weight of said member A holds the bottom or lower end of said member in frictional contact with the driving device 3 that imparts rotary movement to said member. In order that the speed of rotation of the member A may be changed easily, we combine the driving device 3 with the drive shaft 2 in such a way that said driving device can be arranged in different positions along the length of said drive shaft, nearer to or farther away from the longitudinal axis of the member A, as shown in broken lines in Figure 2.

30 Instead of using a friction driving means for transmitting motion to the rotatable striped member A of the pole from the disk of the electric motor, we may use a driving means of the gear type, such as is shown in Figures 4 and 5. In this form of our invention the disk γ of the electric motor is arranged horizontally and connected to a vertically-disposed drive shaft 2^a that is provided at its upper end with a pinion 11 which meshes with a gear 12 fastened to a stub shaft 13 that is attached to the bottom of the rotatable member A at a point in alignment with the longitudinal axis of said member. In other respects the barber pole shown in Figures 4 and 5 is the same as the barber pole shown in Figures 1 to 3, inclusive, and comprises corresponding parts arranged in a similar manner. In the pole shown in Figures 4 and 5 the lubricating means comprises an additional pocket 5^a for holding a lubricating medium, arranged so that it will keep the bearing of the stub shaft 12 properly lubricated.

Having thus described our invention, what we claim as new and desire to secure by Letters Patent is:

1. A barber pole provided with a vertically-disposed rotatable striped member, a housing for said member comprising a bottom supporting bracket, an electric induction motor of the disk type, a drive shaft connected to the disk of said motor, a driving means for transmitting rotary motion to said rotatable member from said drive shaft, a supporting frame for said motor, drive shaft,

and driving means that is detachably connected to said supporting bracket, and a lubricating means combined with said frame and capable of being replenished from the exterior of the pole for keeping said drive shaft in a lubricated condition. 70

2. A barber pole provided with a vertically-disposed striped member, a transparent housing or casing surrounding said member, top and bottom supporting brackets combined with said transparent housing, a frame detachably connected to the bottom supporting bracket, and an electrically-actuated operating mechanism for said rotatable member combined with said frame to form a complete unit that can be easily removed from said bottom bracket. 75

3. A barber pole provided with a vertically-disposed rotatable striped member, an electric induction motor of the disk type arranged at the lower end of said member, a drive shaft connected with the disk of said motor, and a friction driving device on said shaft that is maintained in frictional engagement with said rotatable member by the weight of said member. 80

4. A barber pole provided with a rotatable striped member, a housing for said member comprising a bottom supporting bracket, an electric induction motor of the disk type, a sustaining frame for said motor detachably connected to said bottom bracket, a drive shaft journaled in said frame and connected with the disk of said motor, and a friction driving device on said shaft arranged so that the weight of said rotatable member will cause the bottom of said member to remain in frictional engagement with said driving device. 95

5. A barber pole provided with a vertically-disposed rotatable striped member, a housing for said member comprising a supporting bracket arranged at the lower end of said member, a frame detachably connected to said bracket, a centering pin on said frame that is adapted to enter a hole in the bottom of said rotatable member and hold said member centered with relation to said housing, an electric induction motor of the disk type combined with said frame to form a unit that can be easily removed from said bracket, and a friction driving means operated by the disk of said motor and held in frictional engagement with said striped member by the weight of said member. 100
